CHARLES H. TOMLINSON, OF MANSFIELD, OHIO, ASSIGNOR TO THE TOMLINSON COUPLER COMPANY, OF MANSFIELD, OHIO, A CORPORATION OF OHIO.

CAR COUPLER.

Application filed January 24, 1920. Serial No. 353,720.

This invention has for its object the provision of a device of the class named which shall be of improved construction and operation. The invention is exemplified in the combination and arrangement of parts shown in the accompanying drawings and described in the following specification, and it is more particularly pointed out in the appended claims.

10 In the drawings

Fig. 1 is a top plan view of two cars in a train connected by a coupler embodying one form of the present invention.

15 Fig. 2 is a side elevation with parts in section of the mechanism shown in Fig. 1;

Fig. 3 is a vertical sectional view of a car coupler such as that shown in Figs. 1 and 2 but on a scale larger than that of the previous figures;

20 Fig. 4 shows one part of the coupler in a different position from that of Fig. 3;

Fig. 5 is a vertical section substantially on line 5—5 of Fig. 3;

25 Fig. 6 is a fragmentary elevation showing a slight modification of one part of the coupler;

Fig. 7 is a bottom plan view of the portion of the coupler at the right in Fig. 3;

30 Fig. 8 is a vertical section of the portion of the coupler at the right in Fig. 3 showing a modification of one of the parts;

Fig. 9 is a vertical sectional view of a somewhat modified form of coupler;

35 Fig. 10 is a top plan view of the coupler shown in Fig. 9.

Although the car coupler embraced in the present invention is applicable to cars of various forms, it is especially applicable to cars or trucks which run upon the supporting surface without tracks and which are provided with casters or movable wheels at one end to permit the cars or trucks to be readily turned from one direction to another. Such cars are extensively used in factories having extended floor space to transfer material from one part of the factory to another and are frequently coupled in trains having a number of cars.

40 Referring first to the embodiment of the invention shown in Figs. 1 to 7, the numeral 20 designates a car body the front end of which is provided with a pair of caster wheels 21 provided with swivel supports 22 to permit the car to be readily turned from one direction to another. The rear portion

of the cars as shown at the right in Figs. 1 and 2 is provided with a stationary axle 23 having wheels 24 rotatably carried thereby. A pair of brackets 26 are secured to the front portion of the car body 20 in spaced relation to one another and support a horizontal pivot pin 27 upon which is mounted a coupling rod 28. The coupling rod 28 is free to swing vertically upon the pivot 27 as an axis but is held against lateral movement relative to the car body so that any movement of the rod 28 in a lateral direction will swing the body of the car in unison therewith and thus direct the course of travel of the car. The rod 28 in the rear of the pivot pin 27 is provided with a socket 29 in which the plunger 30 is mounted. The plunger 30 is forced upwardly by a coil spring 31 and its upward movement is limited by a tail-piece 32 and nut 33. The plunger 30 bears upon the lower surface of the car body and limits the downward movement of the coupler rod 28.

45 The forward end of the coupler rod 28 is provided with a head-piece 34 which has its forward end tapered to facilitate entrance thereof into a socket member 35 comprising the complementary coupler. The member 35 is provided with a bell-shaped portion 36 to guide the head 34 into coupled relation therewith. The socket member 35 is proportioned to fit accurately the head 34 at its maximum diameter and the head tapers to form a neck 37 in the rear of the portion of maximum size. A latch 38 is mounted on a pivot 39 supported by ears 40 extending downwardly from the socket member 35. The latch 38 is provided with a bearing surface 41 arranged to grip the tapered portion of the neck 37 and hold the parts 28 and 35 in coupled relation. It will be seen that any draw-bar pull on the member 28 serves to produce a tighter grip of the latch 38 upon the head 34. The latch 38 is provided with a tail-piece 42 which carries arms 43 extending laterally therefrom. Rods 44 are connected with the arms 43 and extend into cup-shaped members 45 at the sides of the socket member 35. Coil springs 46 cooperate with the rods 44 to resiliently hold the latch 38 in locking position. When two couplers are moved together the head 34 will be guided by the bell 36 into the socket member 35, and the spring 31 and pivot 27 will permit of vertical displacement of the

coupler rod 28 to bring the parts into proper vertical alignment. As the head 34 enters the socket 35 it will press the latch 38 downwardly to permit the head to move past the latch into coupled position. The springs 46 will then return the latch into holding relation in the rear of the head 34.

The socket member 35 is pivotally supported by a pair of ears 50 which extend downwardly from a pivot 51. The pivot 51 is rotatably mounted in a bearing 52 formed on a plate 53 which is secured to the rear of the car body 20. The socket member 35 is journaled on a pivot pin 54 carried by ears 50. The pivot member 51 is held in place by a cap screw 55 and a lock washer 55'. An uncoupling pin or plunger 56 extends downwardly through a central opening in the cap screw 55 and passes through elongated transverse openings in the socket member 35 and through a transverse opening in pivot pin 54. The lower end of the plunger 56 bears upon the tailpiece 42, as illustrated in Fig. 3, so that the parts may be uncoupled by pressure or a blow upon the upper end of the plunger. It will be observed that the uncoupling pin 56 passes through the center of motion of the socket member 35 both with respect to the lateral pivotal motion of the socket member, as well as the vertical motion thereof. This permits the uncoupling of the parts irrespective of the position of the socket member and the uncoupling pin 56 remains in the same position for all angles to which the socket member is moved. When the plunger 56 is forced downwardly into the position shown in broken lines in Fig. 3, the latch 38 and tail-piece 42 will be moved from full line to broken line position as shown in that figure and the coupler parts will then readily move apart.

It will be apparent that the front or leading car may swing from one side to the other as the direction of the train of cars is changed, and the socket member 35 will rotate about its pivot 51. As the car is drawn to one side or the other the lateral strain upon the coupling rod 28 will draw the front portion of the following car so that it will substantially track the rear wheels of the front car. When the cars are moved into coupled relation their movement toward one another is limited by a shoulder 57 which engages a corresponding recess at the base of the bell-shaped member 36. When the parts are uncoupled the bar 28 may be moved upwardly about its pivot 27 into the position shown in Fig. 4 and it may be retained in this position by a catch 59. In this position of the bar 28 an abutment block 60 on the lower face of the bar 28 is brought into position to engage the bell-shaped portion 36 of the socket member 35 in the rear of an adjacent

car, so that when it is desired one car may be given a push from another without causing the two cars to be coupled together. The coupling bar 28 may, if desired, be provided with a laterally extending opening through which a cross-bar 61 may be inserted to form a hand-hold by which the car may be drawn, using the bar 28 as a tongue when it is uncoupled from other cars on a train. The coil springs 46 may be replaced by helical springs shown at 62 in Fig. 6 or by a counterweight shown at 63 in Fig. 8, but the operation of these modified structures is essentially the same as that of the form shown in Figs. 3 and 5.

In some cases it may be desirable to have both ends of the cars equipped with similar couplers and an arrangement for this purpose is illustrated in Figs. 9 and 10. In these figures a draw-bar 65 is pivotally connected with the car 20 at 66 and is supported upon an arc-shaped rod 67 secured to the lower face of the car body 20 by suitable fastening members 68. The rod 67 passes through an opening in a flange 69 on the draw-bar 65 and coil springs 70 surround the rod 67 on each side of the flange 69. The draw-bar 65 is thus resiliently held against lateral displacement from its central position. A socket member 71 is carried by a pivot pin 72 supported by ears 73 on the draw-bar 65. The socket member 71 is provided with a bell 74 similar to that shown at 36 in the form of the invention previously described. A spring plunger 75 limits the downward movement of the socket member 71 in a manner similar to the plunger 30 in the previously described form of the invention. A latch 76 is pivotally mounted at 77 beneath the socket member 71 and operates in the same way as the latch 38 previously described. An uncoupling plunger 78 has its lower end arranged to engage a tail-piece 79 on the latch 76 so that downward pressure on the plunger will release the latch 76. Both the front and rear ends of the cars are equipped with the same form of coupling mechanism and a coupling pin 80 having duplicate heads 81 on opposite ends is used for joining the couplers of two connected cars. It is apparent that when either of the latches 76 is released the coupling pin 81 will remain attached to the socket member of the opposite car so that it will be in position to re-engage the socket member from which it has been uncoupled or a similar socket member on another car. It will be apparent that a car equipped with a socket member like that shown in Figs. 9 and 10 may be coupled with a car having a coupling rod like that shown in Figs. 1 and 2, and it will also be apparent that the socket member shown in Figs. 1 and 2 may be connected with the form of coupling shown in Figs. 9

and 10 where a separable coupling bar is used.

Other combinations of the various forms of couplers will readily suggest themselves 5 to those skilled in the art.

I claim:

1. In combination, a car having front wheels laterally movable thereon to permit lateral turning of said car, a coupling bar 10 carried by the front end of said car and projecting forwardly therefrom, means for holding said bar against lateral movement relative to said car while permitting vertical pivotal movement of said bar, means for 15 limiting the downward pivotal movement of said bar and a second car having a complementary coupler pivoted thereon adjacent said car and arranged to be detachedly connected with said bar.
- 20 2. A car coupler comprising a coupling member having means thereon for securing said member to a complementary member of a cooperating coupler, said first named member being movable into one position to perform its coupling function and into a different position to provide an abutment for transmitting the pushing force between two cars without coupling said cars to one another, said securing means being out of position for cooperation with said complementary member when in said second mentioned position.
- 30 3. A car coupler comprising a coupling bar having means thereon for securing said bar to a complementary member of a cooperating coupler, means for pivotally supporting said bar to permit said bar to be moved into one position to cooperate with said complementary member for securing two cars to one another and into another position in which said securing means is out of position for cooperation with its complementary member and said bar is inoperative as a coupling member, and means on 40 said bar for transmitting a pushing force between said cars without coupling said cars together.
- 40 4. A car coupler comprising a bracket member secured to a car and having a horizontal pivot thereon, a coupling bar mounted on said pivot, a spring pressed member carried by said coupling bar on the side of said pivot adjacent said car, said member being arranged to engage the underside of said car to limit the downward pivotal movement of the outer end of said bar and an abutment member on said bar arranged to be moved into position to engage the coupler of a different car when said bar is swung upwardly into inoperative position.
- 50 5. A car coupling mechanism comprising a coupling member movable into one position to automatically couple two cars when brought together, said coupling member being movable out of said position to permit

said cars to butt against one another without being coupled together, an abutment element on said coupling member for providing abutment for said cars, and means for yieldingly holding said coupling member in position 70 for coupling engagement with a cooperating coupler.

6. Coupling mechanism comprising a bar pivotally mounted on the front end of a car to swing vertically thereon, but held 75 against lateral movement relative thereto, resilient means for limiting the downward movement of said member, but permitting free movement thereof upwardly, a complementary coupling member pivotally mounted 80 on a car to be connected with said first named car, said complementary member being arranged to swing vertically and laterally, resilient means for limiting the vertical downward movement of said complementary 85 coupling member but permitting free movement thereof upwardly, a latch arranged to automatically connect said coupling members when said cars are brought together 90 in coupled relation to one another and means for releasing said latch to permit said cars to be separated from one another.

7. In combination, a coupling head for a vehicle, means for supporting said head for pivotal movement on said vehicle while said head remains in coupled relation with another vehicle, and an uncoupling device for said member extending through the pivotal center of said movement.

8. A car coupler comprising a female 100 coupling member pivoted to swing in two directions, and an uncoupling device passing through both pivotal centers of movement of said member.

9. A coupling device comprising a coupling member pivoted to swing both vertically and laterally, and an uncoupling pin arranged in the axis of movement of said member in one direction and passing through the pivotal center of movement of 110 said member in the other direction.

10. A coupling device comprising a female coupling member pivoted to swing vertically and laterally, and an uncoupling device arranged in the axis of lateral movement of said member and passing through the axis of vertical movement of said member.

11. A coupling device comprising a coupling member, a pivot pin about which said member is free to swing while said member remains in coupled relation with a complementary coupling member, and an uncoupling rod extending through a transverse opening in said pivot pin.

12. An uncoupling device comprising a coupling member, a pivoted head for supporting said member to swing laterally, a pivot pin for securing said member to said pivot head to permit said member to swing

- vertically, and an uncoupling pin arranged in the axis of said pivot head and passing through a transverse opening in said pivot pin.
13. A coupling device comprising a coupling member, a lock for holding said member in coupled relation with a complementary member, means for supporting said coupling member for vertical and lateral pivotal movement, and an uncoupling pin extending through the center of both movements of said member and arranged to engage said lock to uncouple said members.
14. A car coupler comprising a female coupling member pivoted for vertical and lateral movement, a male member, means for locking said members in coupled relation to one another, and an uncoupling pin extending through the axis of pivotal movement of said female member and arranged to engage said lock to uncouple said members from one another.

In testimony whereof I have signed my name to this specification on this 20th day of January, A. D. 1920.

CHARLES H. TOMLINSON.
